Shirley Gathen

Attorney

UNITED STATES PATENT OFFICE

1,974,623

HOOD CATCH

Raymond G. Moore, Bridgeport, Conn., assignor
to The Bassick Company, Bridgeport, Conn., a
corporation of Connecticut

Application March 20, 1933, Serial No. 661,656

8 Claims. (Cl. 292—228)

The present invention relates to hood catches for securing the hoods of automobiles and has for an object to provide a hood catch of simple construction and attractive appearance which 5 may be operated with facility, and will effectually hold the hood downwardly and inwardly against looseness and rattling. Another object is to provide a hood catch in which the handle and latching means will be exteriorly disposed while the 10 tensioning mechanism is interiorly disposed, thus providing a catch which may be easily and positively operated, and which at the same time will present a neat and inconspicuous appearance, free from unsightly mechanism, and which lends 15 itself to streamline design, harmonizing with other parts of the automobile structure.

Another object is to provide a catch which may be horizontally disposed, out of relation with the sill, so that it can be conveniently reached and 20 will in no way interfere with other parts of the automobile. It is also proposed to provide a catch which cannot fail to be properly engaged, the engaging catch and keeper parts being at all 25 times exposed, and in no danger of being fowled or obscured by other parts of the automobile structure.

A still further object is to provide a catch in which spring means is provided in such relation 30 as to exert both an inward and downward pressure on the hood.

With the above and other objects in view, an embodiment of the invention is shown in the accompanying drawing and this embodiment will be hereinafter more fully described with reference 35 thereto, and the invention will be finally pointed out in the claims.

In the drawing:

Fig. 1 is a front elevation of one corner of an automobile hood and the adjacent cowl and sill 40 structure, and showing the hood catch according to the illustrated exemplary embodiment of the invention, attached thereto.

Fig. 2 is a vertical sectional view, taken along the line 2—2 of Fig. 1.

Fig. 3 is a horizontal sectional view, taken along the line 3—3 of Fig. 1 and showing the catch in plan.

Fig. 4 is a rear elevation of the catch, and showing in dot-and-dash lines the upward and 50 downward limits of movement of the handle and catch element.

Fig. 5 is a vertical sectional view taken along the line 5—5 of Fig. 1, and showing the catch in end elevation.

55 Similar reference characters indicate corre-

sponding parts throughout the several figures of the drawing.

Referring to the drawing the hood 10 is adapted to close in the usual manner against the lacings 11, provided along the inset marginal edge 60 portions 12 of the radiator frame and cowl structures 13 (only one being shown), and at each end of the hood, and adapted to cooperate with keepers provided on the radiator frame and cowl structures, hood catches according to the illustrated exemplary embodiment of the invention 65 are mounted.

The hood catch comprises a mounting plate 14, adapted to be riveted, spot-welded, or otherwise suitably secured to the inner side of the hood, 70 preferably adjacent one of the lower corners, although if desired it may be at a substantially higher point than that illustrated.

A bearing opening 15 is provided in the plate and has an outwardly turned bearing flange which 75 engages in an opening 16 in the hood, the edge of the flange projecting slightly beyond the outer surface of the hood.

Upon the plate 14 an arched bridge-like plate 17 having flattened ends 18—18 is secured as by 80 spot-welding the ends 18—18 to the plate 14, and is provided with an opening 19 in axial alignment with the bearing opening 15, this opening being of greater diameter than the handle shaft engaged therein, and presently to be more fully described; so that said shaft may have limited tilting movement, the clearance in the bearing opening 15 being sufficient to permit this. 85

The upright edge of the plate, disposed away from the end of the hood, is of arcuate form and 90 has an arcuate flange 20 bent upwardly therefrom, this flange being concentric to the axis of the bearing openings 15 and 19. At the upper end of the flange a projecting stop lug 21 is provided 95 having an inclined abutment face 22 for cooperation with the spring presently to be more fully described. A notch 23 is provided adjacent the lower end of the flange 20 into which the spring engages in the inoperative position of the catch.

The handle 24 is provided at its inner end with 100 a flange 25 and a shaft extension 26, the latter having bearing in the bearing opening 15 with sufficient looseness to permit of a slight tilt, permitted by the diameter of the opening 19 being larger than the shaft so that the latter is spaced 105 from the wall of said opening. The shaft is provided at its inwardly projecting end portion with flats 27—27 at each side for the non-rotatable mounting thereon of a bar 28, having a correspondingly shaped opening therein, the bar being 110

secured against the end shoulders of the flat surfaces by a washer 29, non-rotatably mounted on the shaft end, and a cotter pin 30 inserted through the shaft end.

5 One end of the bar is bent downwardly and outwardly to provide a foot portion 31, normally spaced from the plate, as shown in Fig. 4, to permit limited tilting movement of the bar. The other end 32 is bent into a plane inclined with 10 respect to the longitudinal direction of the bar downwardly toward the surface of the plate and also inclined transversely downwardly toward the upper edge. Upon this inclined portion 32 a coil spring 33 is secured at its inner end by means of 15 a clip 34 and its outer end rides upon the edge of the flange 20 and is adapted in the operative position of the catch to be tensioned through abutment with the inclined surface 22 of the stop lug 21, the inclinations of the spring end and the 20 surface 21 being substantially the same. Stop lugs 35 and 36 are struck from the plate 14 and are adapted to limit the movement of the bar 28 in its inoperative and depressed keeper engaging 25 position as indicated in dot-and-dash lines in Fig. 4.

In the operative position the force of the spring is applied to the handle to press its outer end upwardly and also to tilt it away from the hood, this action resulting in a downward and inward 30 pressure being applied to the hood, and as will presently more fully appear.

The handle 24 is bent inwardly at its outer end toward the hood and is provided with a longitudinally bent keeper engaging nose or catch portion 37 projecting beyond the end of the hood in the operative position.

The keeper comprises a base plate 38 and a right angularly bent hook flange 39, having a catch engaging recess 40, the outer wall of which is vertically disposed. The plate 38 is preferably secured at the inner side of the cowl or radiator frame 13, as by rivets 41, and the flange 39 projects through a slot opening 42 in the cowl or frame.

45 In operation, the hood is drawn downwardly by downward pressure on the handles 24-24 at each end of the hood, the abutment of the foot portion 31 of the bar 28 against the stop lug 36 causing the downward pressure of the handles to 50 be firmly transmitted to the hood, so that it can be effectually pulled down to its full limit with facility. As shown in dot-and-dash lines in Fig. 4, the handle is swung below the horizontal operative position, the hood being swung outwardly as it is pressed down to clear the keeper. When 55 fully pulled down it is pressed inwardly against the lacings, and upon release of the handle the spring 33 which has been tensioned through abutment of its end with the inclined surface 22 presses it upwardly engaging the catch end 37 with the keeper recess 40, thus retaining the hood closed and exerting a downward pressure thereon. At the same time the angular pressure of the spring on the bar 28 tends to tilt it away from the 60 plate 14 at its spring carrying end and toward the plate at its foot end 31, thus forcing the catch end 37 tightly against the outer face of the keeper and exerting an inward pressure on the hood pressing it firmly against the lacings. To disengage the catch the handle is pressed downwardly, the hood swung outwardly and the handle then 65 swung to its raised position with the foot portion 31 abutting the stop lug 35, as indicated in dot-and-dash lines in Fig. 4.

70 I have illustrated and described a preferred and

satisfactory embodiment of the invention, but it will be obvious that changes may be made therein, within the spirit and scope thereof, as defined in the appended claims.

Having thus described my invention what I 80 claim and desire to secure by Letters Patent is:—

1. Automobile hood fastening means for engaging a keeper disposed upon a fixed part in relation to the end of the hood, comprising catch means adapted to be mounted upon the hood comprising an exterior finger gripping portion and a keeper engaging portion, said catch means adapted to swing about a tilttable axis, spring means associated with said catch means adapted to both swing and tilt said catch means, and said catch means adapted through said swinging and tilting to engage said keeper to exert downward and inward pressure on the hood.

2. Automobile hood fastening means for engaging a keeper disposed upon a fixed part in relation to the end of the hood, comprising a mounting fixture adapted to be secured to the hood, catch means carried by said mounting fixture comprising an exterior finger gripping portion and a keeper engaging catch portion, and spring means 95 associated with said catch means disposed at an inclined angle to said mounting fixture adapted to both swing and tilt said catch means, and said catch means adapted through said swinging and tilting to engage said keeper to exert downward and inward pressure on the hood.

3. Automobile hood fastening means for engaging a keeper disposed upon a fixed part in relation to the end of the hood, comprising a mounting fixture adapted to be secured to the hood, 110 catch means carried by said mounting fixture comprising a finger gripping portion, a keeper engaging portion at one end, and a mounting shaft at the other end having rotatable and tilting bearing in said mounting fixture, and spring and abutment means cooperating between said catch means and said mounting fixture disposed at an inclined angle to said mounting fixture adapted to both swing and tilt said catch means, and said catch means adapted through said swinging and 115 tilting to engage said keeper to exert downward and inward pressure on the hood.

4. Automobile hood fastening means for engaging a keeper disposed upon a fixed part in relation to the end of the hood, comprising a mounting fixture adapted to be secured to the hood, 120 catch means carried by said mounting fixture comprising a finger gripping portion, a keeper engaging portion at one end, and a mounting shaft at the other end having rotatable and tilt- 125 ing bearing in said mounting fixture, spring means carried by said catch means, and inclined abutment means carried by said mounting fixture adapted upon swinging of said catch means to tension said spring means and through its incli- 130 nation to exert a tilting pressure on said catch means, said catch means adapted through said swinging and tilting to engage said keeper to exert downward and inward pressure on the hood.

5. Automobile hood fastening means for en- 140 gaging a keeper disposed upon a fixed part in relation to the end of the hood, comprising a mount- 145 ing fixture adapted to be secured to the hood, catch means carried by said mounting fixture comprising a finger gripping portion, a keeper engaging portion at one end, and a mounting shaft at the other end having rotatable and tilt- 150 ing bearing in said mounting fixture, spring means carried by said catch means disposed at an inclined angle to said mounting fixture, and abut-

- ment means carried by said mounting fixture adapted upon swinging of said catch means to tension said spring means and through the inclination of said spring means to exert a tilting pressure on said catch means, said catch means adapted through said swinging and tilting to engage said keeper to exert downward and inward pressure on the hood. 6. Automobile hood fastening means for engaging a keeper disposed upon a fixed part in relation to the end of the hood, comprising a mounting fixture adapted to be secured to the hood, catch means carried by said mounting fixture comprising a finger gripping portion, a keeper engaging portion at one end, and a mounting shaft at the other end having rotatable and tilting bearing in said mounting fixture, spring means carried by said catch means disposed at an inclined angle to the plane of rotation of said shaft, an arcuate bearing surface carried by said mounting fixture disposed concentric to the axis of said shaft and upon which said spring means slides as said catch means is swung, abutment means at one end of said bearing surface adapted upon swinging of said catch means to abut and tension said spring means and through the inclination of said spring means to exert a tilting pressure on said catch means, said catch means adapted through said swinging and tilting to exert downward and inward pressure on the hood, and recessed means at the other end of said bearing surface adapted to be engaged by said spring means to releasably retain said catch means in inoperative position. 7. Automobile hood fastening means for engaging a keeper disposed upon a fixed part in relation to the end of the hood, comprising catch means mounted exteriorly of the hood comprising a finger gripping portion and a keeper engaging portion, said catch means adapted to swing about a tilttable axis, spring means associated with said catch means adapted to both swing and tilt said catch means, and adapted through said swinging and tilting to engage said keeper to exert downward and inward pressure on the hood, and stop means fixed with relation to the hood adapted to limit the depressing of the catch means and whereby downward pressure on said catch means is positively transmitted to the hood.
